UNITED STATES PATENT OFFICE.

JOSEPH JACOBS, OF SOUTH NORWALK, CONNECTICUT, ASSIGNOR TO WEBBING & EDGING CORPORATION, OF NEW YORK, N. Y., A CORPORATION OF NEW YORK.

DESIGN FOR BIAS TRIMMING.

Application filed June 4, 1924. Serial No. 9,793. Term of patent 3½ years.

To all whom it may concern:

Be it known that I, JOSEPH JACOBS, a citizen of the United States, residing at South Norwalk, in the county of Fairfield, State of Connecticut, have invented a new, original, and ornamental Design for Bias Trimming, of which the following is a specification, reference being had to the accompanying drawing, forming part thereof.

The figure is a plan view of a piece of bias trimming showing my new design.

I claim:

The ornamental design for bias trimming substantially as shown.

JOSEPH JACOBS.
